SINK MOUNTING

John E. Schuck, Granite City, Ill.

Application January 27, 1954, Serial No. 406,481

3 Claims. (Cl. 4—187)

This invention relates to sink mountings, and more particularly to means for mounting a sink in an opening in a drainboard.

Among the several objects of the invention may be noted the provision of means for mounting a sink, of the type having a flange around its rim, in an opening in a drainboard, which makes it possible easily to install the sink in the drainboard entirely from above the latter after the drainboard has been installed; the provision of a mounting of this class which is adapted for the installation of sinks of various thicknesses; the provision of a mounting of this class adapted for making a waterproof installation of the sink in the opening in the drainboard; and the provision of a mounting having the stated features which is economical to manufacture. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

Fig. 1 is a plan view of a sink installed in a drainboard by means of this invention, the drainboard being broken away around the sink;

Fig. 2 is an enlarged vertical section taken on line 2—2 of Fig. 1;

Fig. 3 is a horizontal section taken on line 3—3 of Fig. 2;

Fig. 4 is a perspective view of a fragment of a frame element of the invention;

Fig. 5 is a perspective view of a fragment of a sealer ring element of the invention;

Fig. 6 is a perspective view of a lug element of the invention; and,

Fig. 7 is a plan view of Fig. 6.

Corresponding reference characters indicate corresponding parts throughout the several views of the drawings.

Referring to the drawings, reference character 1 designates a conventional sink of a type having an outwardly projecting flat flange 3 all around its rim. As herein illustrated, the sink is rectangular in plan with rounded corners. It is shown as mounted in an opening 5 in a drainboard 7. The latter is illustrated as consisting of the usual plywood board with a facing 9 of a material such as linoleum, or one of the plastics such as the one sold under the trade name Formica. The opening 5, as cut in the board 7, corresponds in outline to the outline of the edge of the flange 3, being somewhat larger than the latter for receiving a frame 11. This frame comprises a metal ring of rectangular outline. The internal dimensions of the frame correspond to the outside dimensions of the sink flange 3 with some clearance; and the frame is adapted to receive the sink from above. The opening 5 is cut in accordance with the external dimensions of the frame with some clearance; and the frame is adapted to be set into the opening from above. The frame may

2

be used if desired as a template for marking the drainboard for cutting opening 5.

The frame has an outwardly projecting upper flange 13 adapted to bear on the top of the drainboard surrounding the opening 5. The frame is of substantial thickness and has screw holes 15 for receiving screws 17 threaded into the edge of the drainboard around the opening 5 for securing the frame in place in the opening. In the inside face of the frame adjacent its upper edge is a groove 19 adapted to receive a metal sealing ring 21. The ring has a downturned flange or lip 23 at its inner edge. It is resilient and is split as indicated at 25 so that it may be collapsed to be sprung into the groove. As indicated in Fig. 2, the downward lip 23 engages the top of the sink flange 3 when the sink is placed at a proper elevation by properly positioning supporting means 31, to be described.

The frame 11 is provided with an upper set of openings 27 and a lower set of openings 29, each opening 20 adapted to receive a sink-supporting lug 31. As shown in Fig. 4, each opening 27 is triangular form, having an upper side 33 (which may be coincident with the lower edge of the groove 19) and two equal sides 35 which converge toward one another in downward direction to 25 a lower apex 37. The set of openings 27 are all of the same size and are located in a common horizontal plane. The sides 35 of the openings are bevelled to diverge away from one another in outward direction with respect to the frame. The openings 29 are identical to the openings 30 27, and are located in a common horizontal plane below the plane of the series of openings 27. The upper side of each opening 29 is designated 39, its convergent and bevelled sides are designated 41, and its lower apex is designated 43. Openings 27 and 29 are provided in both 35 the sides and ends of the frame. For example, for mounting a sink thirty-two inches long and twenty-one inches wide, there may be four openings 27 and four openings 29 in each long side of the frame, and three openings 27 and three openings 29 in each short side 40 or end of the frame.

The mounting includes a number of the lugs 31 corresponding to the number of openings 27 or 29. Thus, in the above-stated case, fourteen lugs would be provided. As shown best in Figs. 3, 6 and 7, each lug 31 is of triangular cross-section corresponding to the shape of the 45 openings 27 and 29 at the inside of the frame. One side of the lug, designated 45, constitutes its top surface, and its sides are each designated 47. The lug at one end has bevelled grooves 49 adapted to interfit with the bevelled sides of the openings 27 and 29 (see Fig. 3).

Installation of a sink utilizing the mounting means of this invention may be readily carried out after the opening 5 has been cut in the drainboard and subsequent to the installation of the drainboard, as follows:

The frame 11 is set into the opening 5 from above the drainboard, its flange 13 bearing upon the drainboard around the opening. The screws 17 are driven into the drainboard to hold the frame in place. Then, depending on whether the sink flange is relatively thin or relatively thick, a set of the lugs 31 is inserted in either the series 55 of openings 27 or the series of openings 29. In the case of a sink with a relatively thin flange, the set of lugs is fitted in the upper set of openings 27, and in the case of a sink with a relatively thick flange, as illustrated in Fig. 3, the set of lugs is fitted in the lower set of openings 60 29. Insertion of each lug in an opening in the frame may be readily accomplished from above simply by reaching down into the frame, inserting the lug endwise in the opening, and then seating the lug by moving it laterally with respect to the length of the lug and downward with respect to the frame to the position such as 65 shown in Figs. 2 and 3. This locks the lug to the frame, 70

The top surfaces 45 of all the lugs are thereby located in a common horizontal plane at a distance below the groove 19 appropriate to the thickness of the sink flange. Then the sink is set into the opening in the frame from above, its flange bearing on the top surfaces lugs. Finally, 5 the sink is caulked by sealing material, as indicated at 51, and the split sealing ring 21 is sprung into the groove 19 to conceal the caulking material. The lip 23 of the sealing ring 21 then engages the upper surface of the sink flange 3, the ring taking the slanting position shown in Fig. 2. This minimizes the formation of open spaces between the sink flange 3 and sealing ring 21 and efficiently traps the sealing material, as indicated.

It will be observed that the entire series of operations above described may be readily carried out from above, 15 making the installation very simple. The provision of the two vertically spaced series of lug openings 27 and 29, with a set of lugs receivable in either series of openings, takes care of the installation of sinks of different thickness. The particular form for the openings 27 and 29 and the lugs 31 is advantageous in that a firm bearing for the lugs is obtained throughout the entire lengths of the bevelled sides of the openings, thereby precluding any tilting of the lugs. This insures a firm support for the sink in its proper position.

In view of the above, it will be seen that the several objects of the invention are achieved and other advantageous results attained.

As various changes could be made in the above constructions, without departing from the scope of the invention, it is intended that all matter contained in the above description or shown in the accompanying drawings shall be interpreted as illustrative and not in a limiting sense.

I claim:

35

1. Means for mounting a flanged sink in an opening in a drainboard, comprising a frame adapted for reception in the opening in the drainboard and adapted to receive the sink, the frame having an outwardly projecting upper flange adapted to bear on the drainboard around the 40 opening in the drainboard, the frame being formed with a set of openings having sides which converge in down-

ward direction, said sides being bevelled to diverge in outward direction with respect to the frame, and lugs received in the openings, each lug having convergent sides corresponding to the sides of the openings and being formed at one end with bevel grooves in its sides interfitting with the bevelled sides of the openings, the lugs projecting toward the inside of the frame for supporting the sink under its flange.

2. Apparatus for mounting a sink in a horizontal opening in a drainboard, the sink having a flange around its rim, comprising a frame, said frame having an outwardly projecting flange adapted to bear on the drainboard around the opening, supporting means extending inwardly from the frame adapted to carry the sink flange, an inside groove in the frame and located above said supporting means, and a resilient sealing ring adapted to be marginally sprung into said groove so as to extend inwardly over said sink flange, the innermost dimensions of said frame above said supporting means corresponding to the outermost dimensions of said sink flange with clearance, whereby installation may be effected by inserting said frame into said opening from above, inserting the sink from above into the frame and onto said supporting means and inserting said sealing ring from above into said groove and above the sink flange.

3. Apparatus made according to claim 2, wherein said inside groove is near the outside flange of the frame, wherein said sealing ring has a downwardly directed lip at its inner edge for engagement with the top of the sink flange, and wherein said supporting means is adjustable in position up and down upon the inside of said frame to an extent adapted to bring sink flanges of various thicknesses into springing engagement with said downwardly turned lip of the sealing ring.
